CLAIM

The ornamental design for a closure clip, as shown and described.

DESCRIPTION

FIG. 1 is a front perspective view of the closure clip;

FIG. 2 is a top view of the closure clip;

FIG. 3 is a bottom view of the closure clip;

FIG. 4 is a front view of the closure clip;

FIG. 5 is a rear view of the closure clip;

FIG. 6 is a left side view of the closure clip;

FIG. 7 is a right side view of the closure clip; and,

FIG. 8 is a front perspective view of the closure clip shown in a position of use on a reclosable pouch drawn in broken lines.

The broken lines in FIG. 8 depict environmental structure and form no part of the claimed design. The characteristic feature of the design resides in the t-shape and gripping area of the t-shape of the closure clip.
